ABSTRACT: An electrographic recorder is disclosed employing an inking channel having an inking slot bearing against a web pulling roller. The recorder includes an input channel to which input signals to be recorded are applied. The recorder channel measures the input signal and produces a signal trace comprising a latent charge image on an electrographic recording web representative of the input signal to be recorded. The charge image bearing web is pulled by means of a friction drive roller past an electrographic liquid inking slot formed in the side of a hollow inking channel through which liquid electrographic toner is passed. The side of the inking channel containing the inking slot is curved to conform to the curved surface of the drive roller to facilitate forming a liquid seal between the inking slot and the recording web as pulled over the drive roller. Charged toner particles within the inking channel are attracted to the charge image thereby developing same.

In a preferred embodiment a spring bias force is applied to pull the drive roller into engagement with the inking channel to facilitate formation of a seal between the web and the inking slot. In addition, the drive roller is preferably provided with a drive surface formed of a material having a relatively high coefficient of friction and made of a compressible, resilient material to allow foreign particles to pass with the recording web across the slot without destroying the seal or tearing the web.

ELECTROGRAPHIC APPARATUS HAVING AN INKING SLOT BEARING AGAINST A WEB PULLING ROLLER

DESCRIPTION OF THE PRIOR ART

Heretofore, electrographic recorders have been disclosed employing an inking channel having an inking slot formed in one side thereof and bearing against a flat plate over which a recording web is pulled by means of a friction drive roller. Such a recorder apparatus is disclosed and claimed in copending U.S. application Ser. No. 578,801 filed Sept. 12, 1966 now U.S. Pat. No. 3,392,401 and assigned to the same assignee as the present invention.

The problem with such a prior art recorder paper drive apparatus is that the friction drive wheels pull on the electrographic recording paper downstream of the liquid inker. Thus, the drive wheels pull on a wet surface or bear against a wet surface of the web which can result in nonuniform paper drive speeds and the printing of ghost images on the recording web due to the transfer of ink from the images on the web to an idler roller and then back to a subsequent portion of the web. In addition, the provision of the flat plate opposite the inking slot allows the recording paper to deform into the inking slot, due to atmospheric pressure, resulting in uneven wear on the edges of the slot. Uneven wear can make it difficult to form an initial seal with the paper. If the inking channel is pushed into engagement with the plate then small foreign particles carried along with the web are caught at the marginal edges of the inking slot resulting in tearing of the electrographic recording paper.

Therefore, a need exists for an electrographic recording paper drive mechanism and inking channel arrangement wherein the frictional paper drive is not performed on the wet paper and means are provided for pressing the recording paper against the marginal edges of the slot to facilitate formation of a seal in such a manner that foreign particles carried along with the recording paper do not result in loss of the seal with the inking slot or tearing of the recording paper.

SUMMARY OF THE PRESENT INVENTION

The principal object of the present invention is the provision of an improved electrographic inking apparatus.

One feature of the present invention is the provision, in an electrographic inking apparatus, of an inking channel disposed facing a drive roller which pulls the electrographic paper past the inking slot in the inking channel and wherein the marginal edges of the inking slot are curved to conform to the curved surface of the drive roller to facilitate forming a liquid seal between the inking slot and the recording web.

Another feature of the present invention is the same as the preceding feature wherein the curved surface of the drive roller, which faces the recording web, has a substantial coefficient of friction and is made of a compressible resilient material to facilitate sealing between the web and the marginal edges of the inking slot.

Another feature of the present invention is the same as any one or more of the preceding features including means for providing a spring bias force for urging the paper drive roller and inking channel toward each other to sandwich the recording paper therebetween to facilitate formation of the liquid seal between the paper and the inking slot.

Other features and advantages of the present invention will become apparent upon a perusal of the following specification taken in connection with the accompanying drawing wherein:

BRIEF DESCRIPTION OF THE DRAWING

The drawing is a perspective view, partly schematic and partly in block diagram form, depicting an electrographic recorder incorporating features of the present invention.

DESCRIPTION OF THE PREFERRED EMBODIMENTS

Referring now to the drawing there is shown an electrographic recorder 1 incorporating features of the present invention. The recorder 1 includes a pair of input terminals 2 and 3 to which an input signal E_i is applied to be measured and recorded. The input signal was fed to a preamplifier 4 wherein it is amplified and fed to the input of an analog-to-digital converter 5. The analog-to-digital converter tracks the input signal E_i and produces a binary data output 6 representative of the input signal E_i . The binary data output signal 6 is fed to an array of electrographic writing electrodes 7 extending crosswise of an electrographic recording paper 8 having a conductive paper backing and a thin dielectric charge retentive surface facing the array of writing electrodes 7.

A cylindrical frictional drive roller 9, more fully described below, frictionally grips the paper 8 and pulls the paper 8 past the array of writing electrodes 7 from a supply 11. A takeup roll 12 takes up the recording paper 8 after it has passed over the drive roller 9.

The writing electrode array 7 has selected one of its electrodes energized by the output 6 of the analog-to-digital converter 5 for laying down a line charge image on the charge retentive surface of the recording paper 8. The line charge image is a signal trace representative of the input signal E_i to be recorded. Signal writing electrodes 7 cooperate with a second writing electrode plate 14 disposed on the conductive side of the recording paper 8 and operated at a suitable potential such that the writing potential applied to the selected electrode of the array 7 produces approximately minus 500 to minus 900 volts relative to the electrode plate 14.

An electrographic recorder employing an array of writing electrodes energized by the output of an analog-to-digital converter is disclosed and claimed in copending U.S. application Ser. No. 582,767 filed Sept. 28, 1966 now U.S. Pat. No. 3,394,383 and assigned to the same assignee as the present invention.

An electrographic inking channel 15 is disposed facing the drive roller 9. The inking channel 15 includes an inking slot 16 cut through the side wall of the channel 15 and having its marginal edges curved to conform to the curved cylindrical surface of the drive roller 9. Liquid electrographic toner (ink) is supplied to the inking channel 15 from a reservoir 17 by means of a liquid ink line 18. A vacuum pump 19 draws a suitable vacuum on the top of the inking channel 15, as of minus 15 inches of water, by means of a vacuum line 21. The vacuum head drawn on the inking channel 15 causes the liquid ink within the reservoir 17 to be drawn via the liquid line 18 into the inking channel 15 to a predetermined level within the inking channel above the inking slot 16. A float valve controls the conductance of a vacuum bypass line to the reservoir, not shown, for maintaining the liquid level within the inking channel 15 at the desired height. An inking channel supplied with a vacuum head and interconnected to a reservoir and including a bypass float controlled liquid level means is disclosed and claimed in copending U.S. application Ser. No. 577,443 filed Sept. 6, 1966 now U.S. Pat. No. 3,392,706 and assigned to the same assignee as the present invention.

A spring bias force, schematically indicated by a tension spring 23 interconnecting the inking channel 15 and the drive roller 9, causes the drive roller 9 to press the recording paper 8 against the marginal edges of the inking slot 16 to assure formation of a liquid seal therebetween such that a vacuum head may be pulled on the inking channel 15 to draw the ink into the channel 15 and inking slot 16.

The drive roller 9 is preferably made of a compressible resilient material such as a synthetic elastomer as of urethane elastomer or neoprene, which also provides a substantial coefficient of friction between the roller and the conductive backing of the paper 8 to permit frictional drive of the paper 8. The material should also be chemically inert to the liquid toner. The compressible resilient characteristic of the drive roller 9 facilitates formation of the liquid seal between the

paper 8 and the marginal edges of the inking slot 16 and, in addition, permits small foreign particles carried on the surface of the paper 8 to pass the slot 16 without breaking the fluid seal between the paper 8 and the marginal edges of the slot 16. In addition the compressibility of the roller 9 prevents these particles from being lodged between the paper 8 and the marginal edges of the inking slot 16. Trapping of the particles could result in tearing of the paper and loss of the fluid seal. An advantage of frictionally driving the recording paper 8 at the inking slot 15 is that the frictional drive of the paper is obtained on dry paper without the need of an idler roller riding on the wet side of the paper. This avoids transfer of ghost images from the idler roller to the recording paper. In other words, the prior art idler roller is replaced by the inking channel 15.

The drive roller 9 is rotationally driven by means of a belt 25 and a pair of pulleys 26 and 26'. Drive pulley 26' is driven from the shaft of a motor 27, only partially shown. A pair of idler rollers 28 and 29 are disposed on the conductive side of the web on opposite sides of the writing electrode array 7 to assure that the electrographic paper 8 is properly positioned with respect to the writing array 7.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

I claim:

1. In an electrographic apparatus for reproducing an image onto a recording medium, the combination comprising:
a rotating drive roller for engaging and moving the recording medium;
means for rotating the drive roller;
inking means mounted proximate the drive roller and provided with an inking chamber having an inking slot therein for applying ink from the ink chamber to the

recording medium, the marginal edges of the inking slot being curved to conform to the contour of the drive roller with the recording medium positioned therebetween;
biasing means between the drive roller and the inking means for engaging the recording medium between the drive roller and the marginal edges of the inking slot to deter ink leaks and permit the rotating drive roller to move the recording medium; and
vacuum means for establishing a lower than atmospheric pressure in the ink chamber the surface further deterring ink from leaking out of the ink chamber between the marginal edges of the inking slot and the recording medium.

2. The electrographic apparatus of claim 1 wherein the coefficient of friction of the surface of the drive roller is higher than the coefficient of friction of the marginal edges of the inking slot for permitting the drive roller to frictionally engage and move the recording medium.

3. The electrographic apparatus of claim 1 wherein the vacuum means additionally functions to transport and circulate the ink to and through the inking chamber.

4. The electrographic apparatus of claim 1 wherein the bias means is a resilient spring member for urging the drive roller and the marginal edges of the inking slot into sealing engagement with the recording medium positioned therebetween.

5. The electrographic apparatus of claim 1 wherein the curved surface of the drive roller is a compressible resilient material to facilitate sealing between the drive roller and the marginal edges of the inking slot with the recording medium therebetween while permitting foreign particles on the recording medium to compress the curved surface of the drive roller and to pass with the recording medium across the marginal edge of the inking slot.

6. The electrographic apparatus of claim 5 wherein the compressible resilient surface of the drive roller is made of a synthetic elastomer.
